UNITED STATES PATENT OFFICE.

WILLIAM E. LOUDEN, OF LISBON, OHIO.

NUT-LOCK.

No. 831,449.

Specification of Letters Patent.

Patented Sept. 18, 1906.

Application filed February 20, 1906. Serial No. 302,024.

To all whom it may concern:

Be it known that I, WILLIAM E. LOUDEN, a citizen of the United States, residing at Lisbon, in the county of Columbiana and State 5 of Ohio, have invented a new and useful Nut-Lock, of which the following is a specification.

This invention relates more particularly to means for locking against movement the nuts 10 employed in railroad-rail joints and the like.

The principal object is to provide a simple, novel, and effective structure which may be employed in connection with the ordinary rails and splice-bars or fish-plates, will effectively hold the nuts against accidental turning or loosening, and yet will permit the same to be removed and replaced by workmen if it is found desirable or expedient.

In the drawings, Figure 1 is a side elevation of the preferred embodiment of the invention. Fig. 2 is a similar view, but showing the nuts in section. Fig. 3 is a horizontal sectional view through the same. Fig. 4 is a vertical cross-sectional view, and Fig. 5 25 is a detail perspective view, of one of the nuts.

Similar reference-numerals designate corresponding parts in all the figures of the drawings.

In the embodiment illustrated the rails, as 30 usual, comprise a base-flange 6, a tread or head flange 7, and a connecting-web 8. The fish-plates or splice-bars are designated 9, the same fitting against the opposite sides of the web and resting on the base-flange 6, but 35 preferably terminating short of the head 7. Through the fish-plates and web are passed the usual bolts 10, each having a head 11 at one end and a threaded shank 12 at the other.

On the threaded shanks are screwed nuts 40 comprising outer heads 13, angular in cross-section, and inner necks 14, also angular in cross-section. The necks are considerably smaller than the heads and are arranged to abut against the outer face of the adjacent 45 fish-plate or splice-bar, as shown.

For the purpose of holding the above-described nuts against accidental rotation a locking-plate 15 is employed, having a series of longitudinally-disposed keyhole-openings 50 therethrough. Each keyhole-opening comprises an enlarged portion 16 and a contracted portion 17. The larger portions of the keyholes permit the passage of the heads 13 of the nuts, while the smaller portions are 55 too small to permit such passage, said smaller portions, however, snugly receiving the necks

14 of the nuts, and when said necks are located therein they, and consequently the nuts, are held against rotation. This, it is thought, will be apparent by reference to Fig. 2. The 60 locking-plate terminates short of the lower portion of the fish-plate or splice-bar, but is provided at its ends with outwardly-extending lugs 18, having their outer portions projecting beyond the fish-plates and base-flange, the projecting portions being provided with openings 19. Holding-spikes 20, driven through the openings, are engaged in the ties beneath the same, and thus positively hold the locking-plate against longitudinal movement. 70

It will be apparent that the rail-joint may be formed in the ordinary manner, the only care necessary being that the necks of the nuts have certain of their opposite flat faces 75 disposed in horizontal relation. After the bolts have been properly tightened the locking-plate is applied, the heads of the nuts being received through the enlarged portions thereof, after which the locking-plate is 80 moved longitudinally so that the necks 14 are received in the contracted portion 17 of the openings. After being so placed the holding-spikes 20 are driven. It will be apparent that this structure constitutes an effective and positive lock that prevents the accidental loosening of the nuts from the jar and vibration of the passing trains. At the same time by removing the spikes 20 and the locking-plate said nuts may be operated 85 in the ordinary manner, and none of the parts having been injured or defaced in any way they may be employed again without difficulty. 90

From the foregoing it is thought that the 95 construction, operation, and many advantages of the herein-described invention will be apparent to those skilled in the art without further description, and it will be understood that various changes in the size, shape, 100 proportion, and minor details of construction may be resorted to without departing from the spirit or sacrificing any of the advantages of the invention.

Having thus fully described my invention, 105 what I claim as new, and desire to secure by Letters Patent, is—

1. In a nut-lock, the combination with a rail and fish-plate, of a plurality of bolts passing through the rail and fish-plate, nuts 110 threaded on the bolts, said nuts comprising outer heads and inner angular necks of less

cross-sectional area than the heads, a single-piece locking-plate that fits against the fish-plate and has a series of longitudinally-disposed keyhole-openings therein, the larger 5 portions of the openings permitting the passage of the nut-heads, the smaller portions snugly receiving said necks to prevent the turning of the nuts and being of less area than the heads, and spaced outstanding lugs carried 10 by the lower portions of the ends of the locking-plate, and each having a holding-spike-receiving opening, the lower edge of the locking-plate between the lugs being disposed over the base-flange of the rail.

15 2. In a nut-lock, the combination with a rail comprising a head-flange, a base-flange, and a connecting-web, of a fish-plate bearing against the web and having an outstanding lower portion that rests on the base-flange,

20 said fish-plate terminating short of the head-flange, bolts passing through the rail and fish-plates, nuts threaded on the bolts, said nuts comprising outer heads and inner angular necks of less cross-sectional area than the 25 heads, a locking-plate that engages against

the fish-plate and has its upper margin fitted over said fish-plate and against the rail-web between the upper edge of the fish-plate and the head-flange of the rail, said locking-plate furthermore having a series of longitudinally-disposed keyhole-openings therein, the large 30 portions of the openings permitting the passage of the nut-heads, the smaller portions snugly receiving the nut-necks to prevent their turning and being of less area than the heads, said locking-plate having spaced outstanding lugs that extend over and project beyond the outstanding portion of the fish-plate, and means passing through the projecting 35 portions of the lugs for securing the plate against longitudinal movement with respect to the nuts.

In testimony that I claim the foregoing as my own I have hereto affixed my signature in the presence of two witnesses.

WILLIAM E. LOUDEN.
